CASING FOR A WRINGER

Arthur Joseph Lundy, Newtownards, Northern
Ireland, assignor to Short Brothers & Harland
Limited, Newtownards, Northern Ireland

Application October 15, 1952, Serial No. 21,835
In Great Britain August 25, 1952

Term of patent 14 years

(Cl. D49—1)

To all whom it may concern:

Be it known that I, Arthur Joseph Lundy, a subject of the Queen of Great Britain and Northern Ireland, and a resident of Newtownards, County Down, Northern Ireland, have invented a new, original, and ornamental Design for a Casing for a Wringer, of which the following is a specification, reference being had to the accompanying drawing, forming part thereof:

Fig. 1 is a perspective view of a casing for a wringer showing my new design;

Fig. 2 is an end elevational view thereof taken from the right of Fig. 1;

Fig. 3 is a rear elevational view thereof;

Fig. 4 is a bottom plan view thereof, and

Fig. 5 is a sectional view thereof taken on the

line 5—5 of Fig. 1 looking in the direction of the arrows.

I claim:

The ornamental design for a casing for a wringer, as shown.

ARTHUR JOSEPH LUNDY.
